RECLINING CHAIR

Henry P. Glass, Chicago, Ill.

Application October 18, 1957, Serial No. 48,157

Term of patent 7 years

(Cl. D15—1)

FIG. 1

FIG. 2

Figure 1 is a side perspective view of a reclining chair, showing my new design as it appears when in a reclining position; and

Figure 2 is a perspective view thereof as seen from the side opposite Figure 1, and as it appears when in an upright position.

The back is substantially plain.

I claim:

The ornamental design for a reclining chair, as shown and described.
